UNITED STATES PATENT OFFICE

HAROLD C. HATFIELD, OF RACINE, WISCONSIN, ASSIGNOR OF FORTY-NINE PER CENT
TO JOHN F. HUBER, OF RACINE, WISCONSIN

BUFFER PAD

Application filed October 8, 1928. Serial No. 311,078.

This invention pertains to buffer pads, and has primarily for its object to provide a simple, durable, and efficient pad, capable of use upon any surface, regardless of irregularities in its contour.

5 While a buffer pad of the foregoing character has many uses, and applications, in connection with both portable and stationary buffers, the present invention is designed primarily for use upon automobile bodies and the like, wherein a high polish is desired, and the surfaces encountered present great irregularities and numerous corners, impossible to be polished with conventional types of buffers.

10 For accomplishing the purpose of the invention, a flexible, concave pad is provided, which may be faced with any suitable buffing material, such as wool, felt, or sheepskin with the fleece retained thereon, the latter being preferable, in that actual use has demonstrated that it is the most durable material and produces the most desirable finish.

15 With the above and other objects in view, which will appear as the description proceeds, the invention resides in the novel construction, combination and arrangement of parts substantially as hereinafter described and more particularly defined by the appended claims, it being understood that such changes in the precise embodiment of the herein disclosed invention may be made as come within the scope of the claims.

20 In the accompanying drawings is illustrated one complete example of the physical embodiment of the present invention constructed according to the best mode so far devised for the practical application of the principles thereof.

25 Figure 1 is a transverse, sectional view through a buffer pad constructed in accordance with the present invention, and applied to a conventional portable buffer.

Figure 2 is a plan section taken on the line 2—2 of Figure 1.

30 Referring now more particularly to the accompanying drawing, in which the invention is illustrated attached to a portable electric buffer, the numeral 1 designates a motor casing, to which is attached a handle 2. For

convenience of operation, and to obtain the desired gear reduction, the driven shaft 3 is disposed at right angles to the longitudinal axis of the motor housing. While the foregoing type of portable motor driven buffer 55 has been illustrated and described, it will be quite apparent that the present invention may be utilized in connection with buffers of any type, inasmuch as it is not dependent for its operation upon a specific type of design 60 of buffer.

65 The pad comprising the present invention, consists of a concavo-convex annular disc 4 formed from resilient material, such as rubber or the like. While the disc may be formed in various ways, it is preferred to cast the same in the normal shape illustrated. Formed integral with the disc and extending from its convex face, is a central attaching hub 5, in which is embedded a metallic connecting sleeve 6. In casting the disc 4 it is proposed to cast the sleeve directly in the hub, and in order to secure the same therein the upper and lower ends of the sleeve are provided with annular retaining flanges 7, while vertical webs 8 serve to prevent rotation of the sleeve within the hub. A set screw 9 passing through an opening provided in the hub 5 in alignment with a threaded hole 10 provided in the sleeve, serves to lock the sleeve 70 upon the driven shaft 3.

75 While any suitable buffing material may be employed, such as wool, felt, and the like, it is proposed to utilize sheepskin with the fleece retained thereon, inasmuch as the same is highly flexible and produces the most desired finish. Also, the same readily lends itself to secure attachment to the disc, by means of cement, or other suitable adhesive.

80 As illustrated in Figure 1, the entire concave face of the disc 4 is covered with the sheepskin 11, thus, as the pad is forced into contact with a surface, nothing but the buffing material comes into engagement with the same.

85 It will also be noted that the disc 4 is tapered outwardly in cross section to a thin edge, thus providing sufficient rigidity of the disc adjacent its central portion to allow sufficient 90 95 100

pressure to be exerted in the buffing operation, and at the same time providing a maximum flexibility at the outer edge of the disc to permit it to conform to irregular contours.

5 From the foregoing it will be obvious that a very simple, efficient, and durable buffing pad has been produced, which, because of its normal concave buffing face, and its flexibility, is enabled to conform to either convex 10 or concave surfaces, or other irregularities in contour.

I claim:—

15 1. A buffer pad comprising an annular concavo-convex disc of resilient material and provided with an integral hub on its convex face, said disc tapering outwardly in cross section to a thin marginal edge, a metallic sleeve embedded in said hub for receiving a shaft, longitudinal webs on the sleeve extending

20 into said hub to prevent relative movement between said sleeve and hub, means for locking said sleeve on said shaft, and buffing material secured to and covering the entire concave face of said disc.

25 2. A buffer pad comprising an annular concavo-convex disc of resilient material and provided with an integral hub on its convex face, said disc tapering outwardly in cross section to a thin marginal edge, a metallic 30 sleeve embedded in said hub for receiving a shaft, annular flanges on said sleeve and longitudinal webs between the flanges to prevent relative movement between said sleeve and hub, means for locking said sleeve on the 35 shaft and buffing material secured to and covering the entire concave face of the disc.

35 3. A buffer pad comprising an annular concavo-convex disc of resilient material and provided with an integral hub on its convex 40 face, said disc tapering outwardly in cross section to a comparatively thin marginal edge and buffing material secured to and covering the entire concave face of the disc.

45 In testimony that I claim the foregoing I have hereunto set my hand at Racine, in the county of Racine and State of Wisconsin.

HAROLD C. HATFIELD.
